UNITED STATES PATENT OFFICE.

JOSEPH ELON ROSE, OF PORTLAND, OREGON.

ARTIFICIAL TOOTH.

1,423,027.

Specification of Letters Patent.

Patented July 18, 1922.

Original application filed October 7, 1920, Serial No. 415,258. Divided and this application filed September 21, 1921. Serial No. 502,275.

To all whom it may concern:

Be it known that I, JOSEPH ELON ROSE, a citizen of the United States, residing at Portland, county of Multnomah, State of Oregon, have invented a certain new and useful Improvement in Artificial Teeth, of which the following is a specification.

The present invention relates to artificial teeth and has to do more particularly with 10 artificial teeth wherein a crown of gold or other suitable material is provided with a facing of porcelain or like material shaped and colored to simulate a natural tooth. The invention is directed to the production of a 15 new and durable tooth structure.

One object of the invention is to produce an artificial tooth which shall be strong and durable while presenting a neat finish closely simulating a natural tooth. Another object is to produce a novel structure which 20 shall include only a crown and facing which accurately and firmly fit and engage each other. Another object is to so shape the engaging portions of the crown and facing 25 that the latter will be firmly retained in place under all the varied conditions of service.

The present application is a division of my prior application, Serial No. 415,258, 30 filed October 7, 1920.

In carrying out my invention, I provide a crown of one metal throughout which has a front wall comprising a central protruding portion more or less surrounded by a 35 peripheral groove or grooves. The facing of porcelain or like material is shaped so as to accurately fit said protruding portion and grooves and to bear against the same throughout its entire engaging surface. The 40 process for bringing about this result includes several operations. In performing my process I first form a crown so as to fit the prepared tooth and cut away a portion of its face. With the crown in position upon 45 the prepared tooth I then press warm wax into the opening against the tooth. A facing of porcelain or like material is then pressed against the soft wax and the surplus wax trimmed off. The crown, wax and fac- 50 ing may then be removed from the tooth. After the facing is removed from the wax, a mold is made to fit the assembled crown and wax, the crown and wax serving as a pattern. Then the wax is removed from the 55 crown by heating the mold. Then molten

gold or other metal is poured into the mold and the gold occupies the space formerly occupied by the wax. As a result the open face of the crown is closed by a metal wall which accurately fits both the tooth and facing and to which the facing may be readily attached by cement. The facing, itself, is made from a baked porcelain form by grinding it to the desired shape.

It will be seen that in carrying out my 65 invention I am enabled to produce a crown having a porcelain or like facing which may be used on vital teeth. It will also be seen that the metal wall between the facing and the prepared tooth conforms exactly to the 70 irregularities of both the tooth and the facing and thus provides an accurate fit which enables the parts to be readily secured together by cement. Furthermore, the protruding portion of the front wall of the 75 crown together with the peripheral groove and the co-operating surfaces on the facing give the assembled structure a strong and retentive form which greatly strengthens the crown and thereby increases its life and 80 durability. Not only is this true, but by the method I employ, the cutting away of the tooth in preparing it is reduced to a minimum, as it does not need to be shaped so as to fit a particular wall. The construction is 85 such also that the crown may be used as an abutment or anchor for a bridge. There are other features and advantages which will be more particularly pointed out hereinafter while others need not be mentioned since 90 they will be at once apparent to dentists and others skilled in this art.

The invention in its various features and aspects will be more fully understood upon reference to the following detailed description taken in connection with the accompanying drawing, and the scope of the invention will be particularly pointed out in the appended claims.

In said drawing, Fig. 1 is a perspective 100 view of an artificial tooth or crown constructed in accordance with the present invention; Fig. 2 is a vertical section of the crown showing the front cut away so as to provide an open face; Fig. 3 is a similar 105 view of the same crown placed upon the prepared tooth and the open face filled with wax; Fig. 4 is a similar view showing the facing pressed up into engagement with the wax; Fig. 5 is a view of the crown and 110

wax, with the facing removed, secured to the sprue wire in the crucible former; Fig. 6 is a sectional view of a ring mold filled with investment material and the wax burned out, 5 all ready for the pouring of the metal; Fig. 7 is a sectional view of the finished crown removed from the mold, its open front now being closed by a metal wall; Fig. 8 is a similar view of the finished tooth showing 10 the facing secured to the outer surface of the metal wall; Fig. 9 is a perspective view of the finished crown with the facing removed; Fig. 10 is a section through the crown in position upon the prepared tooth, 15 the section being taken on a plane indicated by the line 10—10 of Fig. 8; Fig. 11 is a perspective view of the crown when in the condition shown in Fig. 2; Fig. 12 is a perspective view of a modified tooth, showing 20 a crown and facing of somewhat different shape; Fig. 13 is a vertical section of the crown of said modified tooth, showing the front of the crown cut away so as to provide the open face; Fig. 14 is a perspective view 25 of the same crown after the metal has been poured to form the front wall; Fig. 15 is a section through the finished modified crown in position upon the prepared tooth, the section being taken on a plane indicated by the 30 line 15—15 of Fig. 13. Throughout these views like characters refer to like parts.

Referring to the drawing in detail, 9 designates a crown of gold or other suitable material which may be made in any preferred 35 way. According to one method of forming a crown the distance around the prepared tooth 10 is measured at the gum line by a fine wire and a strip of gold is then cut according to the length of this wire and its 40 ends brought together and soldered or otherwise secured together so as to form a band. This is then placed upon the tooth and trimmed, festooned and otherwise shaped so as to bring about the desired fit. Obviously 45 other ways of producing the crown may be employed. When the crown is produced its face is cut away so as to provide an opening 11. When the open faced crown is upon the tooth this opening is positioned so as to 50 expose the labial face of the prepared tooth. While the crown is in this position upon the tooth a quantity of warm and plastic wax 12 is placed over the tooth at the point where the opening is and the opening is well filled 55 with the wax. Then the facing 13 which has previously been prepared is pressed against the soft wax until the facing has been brought into its desired position, and the surplus wax is trimmed away. The 60 crown, wax and facing are then removed as a unit from the tooth and a mold is prepared. This mold consists of two parts composed of the usual investment material employed by dentists for this class of work. One part of 65 the mold, designated 14, is made by filling

the interior of the crown while the wax and facing are in position, with the investment material and allowing it to harden or set. This portion of the mold then takes the place 70 of the prepared tooth and has the same shape as the tooth. At this stage the facing is removed from the crown. The other portion of the mold, designated 15, is formed by enclosing the form 14 with the crown 9 and the wax 12 upon it, with investment material in 75 a suitable receptacle. In the case illustrated, the receptacle comprises a ring 16 having a crucible former 17 provided with a central opening for a sprue 19. The form 14 with the crown and wax upon it is then attached to 80 the end of the sprue 19 by the wax. Investment material is applied to the crown upon the sprue in the usual manner, and then the ring 16 is placed on the crucible former, over the crown, and filled with investment. This 85 leaves all the parts carried by the sprue completely surrounded by the investment material 15. When the investment material has set, then the crucible former 17 and the sprue 19 are removed, leaving the sprue 90 canal 20. The ring and its contents are then heated and the wax melted and driven off, leaving the void 21 which is to be filled with molten metal. When pouring the metal, the 95 ring and its contents, as illustrated in Fig. 6, is set on the exhaust stand 22 of a suitable exhausting machine. The exhausting air passes through the pores of the investment material and causes the molten metal, as it is poured, to enter all portions of the void 100 21. Although I have described the casting operation as one using an exhaust, other casting methods may be employed. When the metal is poured in this way it fuses with the metal of the crown and provides a solid 105 metal wall 23. This wall closes the opening in the face of the crown 9 and both its front surface and its rear surface have the same shape as did the wax. Consequently, the front face of the wall 23 has a surface which 110 closely and accurately fits the rear wall of the facing 13. Similarly the rear face of the wall 23 accurately fits the adjacent surface of the prepared tooth 10. It will be noted also that the front wall 23 comprises a 115 central protruding portion bounded by peripheral grooves 24. These grooves serve to hold the facing upon the tooth with greater certainty, and the walls of the groove, especially that near the incisal edge 120 of the tooth, serve to transmit the strain of impact upon the facing 13 to the crown 9. In this form of the invention, the overlap of the facing about the incisal edge of the crown greatly improves the esthetic appearance of the finished structure. The two facings are to be used for different types of teeth, long and short. When the metal forming the wall 23 has cooled, the crown 125 with its new wall may be removed from the 130

mold. It is then a simple matter to affix the crown to the prepared tooth by cement. In like manner the facing 13 may be secured to the wall 23 by cement.

5 As before noted I make the facing 13 out of ready-baked porcelain by grinding the same to the desired shape. It will be obvious that crowns of different types of manufacture may be employed. The facings 10 may also be made in different ways and they may also be variously shaped. In any event they should ordinarily be made to cover all the metal of the crown as the tooth is viewed when looking toward the labial surface. In the structure which I have heretofore described, the facing extends over the incisal edge 25 of the crown, overlapping it slightly. As illustrative of a modified arrangement, I have shown a structure in 15 Figs. 12 to 15, inclusive, wherein the crown 9' is provided with an opening 11' which extends only to the incisal edge 25' of the crown. When the crown is completed by the addition of cast wall 23', that wall does not 20 go beyond or include the incisal edge but is of the same length and outline as the opening 11'. In this structure the lower groove 24', or, if you please, the incisal portion of the peripheral groove 24', has a wall 26 25 which receives the pressure applied to the incisal edge of the facing 13'. There are, as before, the vertical portions of the peripheral groove 24' into which the vertical portions of the peripheral ribs of the facing 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

What I claim as new and desire to secure by Letters Patent of the United States is:

1. An artificial tooth comprising a thin

metal crown having walls adapted to closely envelop the end and sides of a prepared natural tooth and to be trimmed and shaped to fit closely against the lingual, labial and other surfaces of the same; the labial crown-wall comprising a central protruding portion partially surrounded by a receding peripheral groove; a relatively thin labial facing accurately fitted and cemented to the protruding and groove portions of the labial crown-wall throughout the entire engaging surface and extending to its incisal edge; the rear surface of the facing and the outer and inner surfaces of the labial crown-wall being irregular, the irregularities of the rear surface of the facing being counterparts of the irregularities of the outer surface of the labial crown-wall and the irregularities of the inner surface of the labial crown-wall being counterparts of the irregularities of the labial surface of the prepared natural tooth, the mated counterparts corresponding reversely to each other thus providing intimate and exact fitting at all points; and the labial crown-wall providing a portion directly behind the incisal edge of the facing, considered in the direction of the tooth's axis, forming an impact-receiving wall to transmit to the crown, impact and strain applied to the facing at its incisal edge.

2. An artificial tooth comprising a thin metal crown having walls adapted to closely envelop the end and sides of a prepared natural tooth and to be trimmed and shaped to fit closely against the lingual, labial and other surfaces of the same; a relatively thin labial facing accurately fitted and cemented to the outer face of the labial crown-wall throughout the entire engaging surface and extending to its incisal edge; the rear surface of the facing and the outer and inner surfaces of the labial crown-wall being irregular, the irregularities of the rear surface of the facing being counterparts of the irregularities of the outer surface of the labial crown-wall and the irregularities of the inner surface of the labial crown-wall being counterparts of the irregularities of the labial surface of the prepared natural tooth, the mated counterparts corresponding reversely to each other thus providing intimate and exact fitting at all points; and the labial crown-wall providing a portion directly behind the incisal edge of the facing, considered in the direction of the tooth's axis, forming an impact-receiving wall to transmit to the crown, impact and strain applied to the facing at its incisal edge.

In witness whereof, I hereunto subscribe my name this 2nd day of September, A. D. 1921.

JOSEPH ELON ROSE.
